JOHN H. DOMKEE, OF WEST HAVEN, CONNECTICUT, ASSIGNOR TO THE WIRE NOVELTY MANUFACTURING COMPANY, OF WEST HAVEN, CONNECTICUT, A CORPORATION OF CONNECTICUT

BUTTON LOOP

Application filed May 1, 1929. Serial No. 359,545.

The invention relates to improvements in button loops particularly adapted for use on garment straps, the loop being specially adapted to be suspended at the end of a strap 5 loop in readiness to be clipped over a button the shank of which may be urged from a button receiving loop into a smaller retaining loop from which it cannot be unintentionally withdrawn, and the objects of the invention 10 are to provide associated wire loops having a suspension loop adapted to contract when the associated loops are made to expand; to provide wire button loops of which the free ends of the wire from one side of the associated loops form a portion of the suspension loop upon an opposite side; and to provide 15 means by which both wire ends may be coupled to permit a relative movement thereof as the suspension loop contracts and re- 20 turns to normal condition. With these and other objects in view as may become apparent from the within disclosures, the invention 25 consists not only of the particular forms herein pointed out and illustrated in the drawing but readily admits of certain other modifications within the scope of what hereinafter may be claimed.

The following is the description of an embodiment of the invention, reference being 30 had to the accompanying drawing in which the Figure 1 is a face view of the button loop, a button shank illustrated in cross-section and being within the button receiving loop; the Figure 2 is a similar view but illustrating 35 the button shank lodged within the yielding throat connecting the receiving and retaining loops; and the Figure 3 is a face view of a modification.

Referring more particularly to the drawing 40 in which similar numbers refer to similar parts, the device comprises a piece of wire of which the middle portion is formed to provide the button retaining loop 1, and the two remaining end portions are formed to provide 45 between them the button receiving loop 2 communicating with the loop 1 by means of the expandable contracted throat 3, as illustrated by the Figures 1 and 2, the wire portions 4 and 5 extending from their respective 50 sides of the associated loops 1 and 2 in crossed

relation that each may contribute to the formation of an opposite side portion of the suspension loop 6 and that, upon any lateral expansion of the associated loops 1 and 2, the suspension loop 6 will laterally contract. 55 The aligned extremities 7 and 8 are normally spaced apart and a ferrule 9 mounted thereover to hold and protect them and to serve as a roller bearing within a strap loop from which the button loop is intended to be 60 suspended.

As the button loop is clipped over a button, the button shank 10 rests within the lower portion of the receiving loop 2 and the wire extremities 7 and 8 are in their normal spaced 65 relation within the ferrule 9, as illustrated by the Figure 1 wherein a portion of the ferrule is broken away to expose the extremities. The shank 10, thus in readiness to be urged passed the contracted throat 3, may be thrust into the retaining loop 1, but in passing the throat 3, as illustrated by the Figure 2, the throat 3, and hence the associated loops 1 and 2 are thereby expanded 70 laterally. Simultaneously with the throat 75 expansion the suspension loop 6 is contracted by reason of the wire forming one side of the associated loops 1 and 2 extending and crossing to form an opposite side portion of the suspension loop 6, the wire extremities 7 and 8 being thereby brought into closer relation 80 within the ferrule 9, as illustrated by the Figure 2 wherein a portion of the ferrule is broken away to expose the extremities as in the previous figure. As soon as the shank 10 passes the throat 3 the wire portions, by reason 85 of the resiliency of the metal, are immediately restored to their normal relative conditions and, once within the retaining loop 1, the button shank 10 is there held against accidental release, an intentional release necessitating again the expansion of the throat 3 and consequent contraction of the suspension loop 6 together with a slight lateral crowding of a strap looped therein. The advantage 90 of having the suspension loop laterally contract within its normal width upon the expansion of the throat portion of the associated loops is most obvious; for in previous button loops of this type both the sus- 95

sension loop and the throat portion expanded at the same time from their respective normal positions with the distinct disadvantage of tending to disassemble the device and of increasing its normal width.

5 In the modified form of the device, as illustrated by the Figure 3, the ferrule is dispensed with and the extremities 7^A and 8^A are lengthened to overlap one another and each provided with an end loop 11 encompassing the other extremity. As the associated loops are made to expand and the suspension loop contracts, each end loop 11 is adapted to slide over the other extremity to permit the functioning of the wire device.

10 15 What I claim is:

1. A button loop comprising a single piece of wire of which a middle portion is bent to form an end and side portions of associated loops intercommunicable by means of an expansible normally contracted throat portion, the remaining portions of the wire being crossed and then extended to each form a half section of a contractible suspension loop, the section of either side of the suspension loop being carried by an opposite side portion of the associated loops.

2. A button loop comprising a single piece of wire of which a middle portion is bent to form an end and side portions of associated loops intercommunicable by means of an expansible normally contracted throat portion, the remaining portions of the wire being crossed and then extended to each form a half section of a contractible suspension loop, and coupling means relatively securing the wire extremities for a limited independent movement.

3. A button loop of resilient wire of which a middle portion is bent to form an end and side portions of associated loops intercommunicable by means of an expansible normally contracted throat portion, the remaining portions of the wire being crossed to close the loops and then extended in cross relation to each form a half section of a suspension loop, each section being integral with an opposite side portion of the associated loops and the free ends of the wire being relatively movable to permit the suspension loop to contract as the associated loops expand.

JOHN H. DOMKEE.
